WO 2010/101890 9/2010

Primary Examiner — Paula Greene

(74) Attorney, Agent, or Firm — Tyler J. Sisk; Casimir Jones S.C.

(57) **CLAIM**

The ornamental design for a headset, as shown and described.

DESCRIPTION

FIG. 1 is a perspective view showing our new design of a headset;

FIG. 2 is a top plan view thereof;

FIG. 3 is a front elevational view thereof;

FIG. 4 is a bottom plan view thereof;

FIG. 5 is a rear elevational view thereof;

FIG. 6 is a right side perspective view thereof; and

FIG. 7 is a left side perspective view thereof.

FIG. 8 is a perspective view showing a portion of our new design of a headset, shown separately for purposes of illustration;

FIG. 9 is a top plan view thereof;

FIG. 10 is a front elevational view thereof;

FIG. 11 is a bottom plan view thereof;

FIG. 12 is a rear elevational view thereof;

FIG. 13 is a right side perspective view thereof; and

FIG. 14 is a left side perspective view thereof.

FIG. 15 is a perspective view showing a portion of our new design of a headset, shown separately for purposes of illustration;

FIG. 16 is a top plan view thereof;

FIG. 17 is a front elevational view thereof, the rear elevational view being a mirror image thereof;

FIG. 18 is a bottom plan view thereof; and,

FIG. 19 is a left side elevational view thereof, the right side elevational view being a mirror image thereof.
